UNITED STATES PATENT OFFICE.

RAY L. CARTER, OF PHOENIX, NEW YORK.

HINGE-RECESS GAUGE.

Application filed April 27, 1927. Serial No. 187,035.

This invention relates to gauges, designed for use by carpenters for locating and cutting the recesses or sockets, in which the leaves of door-butts may be disposed.

5 The object of the invention is to provide a hinge recess gauge or templet, which may be readily applied to door frames, as well as to the doors, for accurately locating and gauging the several hinges, the said templet being especially adapted for supporting and guiding a power-driven routing machine during the cutting of the recesses. A further object is to provide a sectional gauge, one section or unit for each hinge, the said 10 units being similar and each being equipped with adjustable means for laying out recesses of different lengths, breadths and depths, the said units being supported and adjustable towards and from each other, by 15 means of similar recess-gauging members that overlap each other and maintain the true alignment of the said units. And a further object is to provide means for locating and gauging hinge recesses of doors to coincide with molded recesses of metal frames.

A particular object is to improve and simplify the devices shown and described in my United States Patent No. 1,524,234, dated January 25, 1925.

20 The various features and parts of the invention will be understood from the detailed description which follows, and by reference to the accompanying drawings, in which—

Figure 1 is a top plan view of the complete device. Fig. 2 is an edge view of the same. Fig. 3 is a bottom plan view of the gauge. Fig. 4 is a broken rear edge of a door, with a section of the gauge attached, showing a motor-driven router in the act of cutting the top hinge recess. Fig. 5 is a broken front side elevation of the door, and an edge view of the gauge. Fig. 6 is a broken vertical section of a door frame, to which the sectional gauge is applied. Fig. 7 is a horizontal section, taken on line 7—7 of Fig. 6, showing the top end of the gauge. Fig. 8 is a broken edge view, showing the lower unit of Fig. 1 inverted and applied to the top portion of the door. Fig. 9 is a central longitudinal section, taken substantially on line 9—9 of Fig. 6. Fig. 10 is respectively a top and an edge view of one of the gauge members. And Fig. 11 is a cross-section, taken on line 11 of Fig. 1.

In the drawings, 2 represents the jamb of a door-frame, and 2' is the lintel. 3 represents the door.

My complete hinge recess gauge usually consists of three similar sections or units, as A, B and C, whose frames 4 are preferably channel-shaped and interchangeable, as shown in Figs. 7 and 11, and are provided with relatively large medial rectangular openings 4', which afford suitable range for the length and breadth of the recesses, as w , shown in Figs. 6 and 8. The frames 4 comprise bottom portions 4^a, and parallel rails 4^b, the bottoms being recessed longitudinally, as at 4^c, to receive adjustable end-gauging members 5, by which the uppermost recesses of the frame and door are spaced from the lintel 2'. The several frames 4 are connected end to end and suitably spaced by means of similar relatively long flat strips of metal arranged in pairs, as 6—6', whose corresponding ends are over-lapped, and are provided with registering longitudinal slots, as 6^a—6^b, by which the several units may be moved towards and from each other for suitably spacing the hinge recesses. The plates 6—6' are adjustably held together by bolts 7, which play in the slots 6^a—6^b, and also pass through and are suitably spaced by similar elongated spring metal parts 7', the latter preferably being normally curved, as shown in Fig. 9, and exerting sufficient tension when straightened out against the plates 6, to prevent accidental shifting of the parts. The adjustment of the plates 6—6' is maintained by wing-nuts 7^a, and washers 7^b. The plates 6—6' are substantially the same breadth as the channels of the frames 4, and therefore tend to preserve the perfect alignment of the units, and their free ends are mounted upon the bottoms or webs 4^a, to which they are adjustably secured by means of screws 6^c, the latter being threaded into the webs, and playing in the corresponding slots 6^d of the plates. The endwise adjustment of the plates 6—6' regulate the height or length of the recesses w . The end units A and C are each fitted with similar short plates 8, having slots 6^d in which screws 6^e play for rendering said plates adjustable longitudinally like plates 6—6'. The plates 8 are also provided with longitudinal slots 8', in which screws 8^a play, said screws passing through registering slots 5' of the end gauges 5, and being

threaded into the webs 4^a for rendering said gauges adjustable. The corresponding side rails 4^b of the frames are formed with lugs 9, which extend below the bottom plane of the frames, and are threaded to receive transverse adjusting screws 9', by which the breadth of the recesses may be regulated relatively to hinge leaves of different size. The screws 9' are held in the various adjusted positions by locknuts 9^a. When the units A, B and C are applied to the jamb 2, the gauges 5 are engaged with the lintel 2', and the free ends of the screws 9' are brought into engagement with the edge of the jamb (see Figs. 6 and 7), after which the gauge is temporarily secured to the jamb, by means of nails 10, which are carried by the plates 6, 6' and 8. The opposite rails 4^b are fitted with guards 12, which are pivoted by screws 12'. These guards are relatively thin and provide a slight clearance between the door and rabbeted or removable stops, as 13 (see Figs. 6 and 7), for preventing chafing of the face of the door. The guards 12 also serve to properly position the gauge when the latter is applied to the edge of the door, as best seen in Fig. 5. The corresponding rails of the frames 4 are formed with lugs or bosses 14, which are bored out to receive guard members 14', which are applied to the free ends of sections A and C and extend beyond and prevent jamming or otherwise disturbing the adjustment of the end-gauging members 5. The members 5 are preferably graduated in inches and fractions thereof, for enabling the operator to accurately adjust the plates 6 and 8 to hinge butts of different length, as shown in Figs. 1, 3, 6 and 8. The free ends of the members 5 are cut away to provide two gauging surfaces, as 5^a, 5^b, by means of which a slight clearance will occur between the top of the door 3 and the underside of the lintel 2', as will be understood by comparing Figs. 6 and 8.

Where metal door frames are employed, it is the usual practice of the fabricators to mold or depress the hinge recesses in the jambs, thereby rendering it unnecessary for the builder to rout the frame recesses. In order to adapt my recess gauge to metal frames and at the same time facilitate the accurate locating of the recesses in the edge of the door, I provide transversely disposed gauge members 15 arranged in pairs, which are adjustably mounted upon the facing ends of the plates 6, 6' and 8, by means of screws 15', which are threaded into the plates and play in slots 15^a formed in said members. The corresponding ends of the members 15 are formed with gauging points 15^c, which pass through slots 4^d of the rails 4^b, and said points being extended (see Figs. 1 and 3) when the gauge is to be applied to metal frames, and in order to properly determine the position of the hinge leaves in

the molded recesses of the frames, the points 15^c, after first being adjusted for butts of a given length, are inserted in the molded recesses, and the gauge is then maneuvered until the points or the spaces between them substantially coincide with the said recesses. The gauge is then reversed and applied to the edge of the door, as shown in Figs. 5 and 8, for locating and routing the opposing recesses. When the gauge is employed in connection with ordinary wooden door frames, the transverse gauges 15 may be shifted laterally for disposing the points 15^c in the slots 4^d, as shown in Figs. 6 and 8.

Any suitable router may be employed for cutting the recesses, and may comprise a motor 16, the latter being adjustably supported by a base 16', whose plane bottom is adapted to be slidably propelled over the top faces of the rails 4^b. A shaft 17 drives the routing tool 18, the tool projecting below a stationary guide 19 that engages the margins of the openings 4' of the units. By this arrangement the recesses α are smaller than the openings (see Figs. 6 and 8). The facing edges 15^a of the points 15^c define the longitudinal dimension of the recesses and correspond to the range of the tool, as regulated by the guide 19.

In my former patent, the gauge members A—B are shown connected by means of a rod 5 and sleeves 6, said parts being all located at one side of the gauge. This method of connecting and supporting the gauge members has caused considerable trouble and annoyance, because the rods 5, being round and necessarily small in diameter are easily flexed and bent, and the gauge members tending to rotate or twist on the rods, results in throwing said members out of alignment, and otherwise distorting the device, to an extent that renders it difficult to properly apply the gauge to the frames and doors, and effect accurate gauging and routing of the recesses. In the present case, the plates 6—6', which take the place of the old rods (5), are operatively fitted into the channels of frames 4, and said parts may be moved longitudinally without disturbing the alignment of the frames, and when the adjusting screws are tightened, the device will withstand considerable rough handling and use, without danger of distorting the device. The relatively broad connecting plates render it impossible to flex the gauge laterally, and since the said plates are reinforced by being overlapped, as well as by the relatively broad seats afforded by the frames 4, there is no danger of the parts being bent or otherwise rendered unserviceable.

Having thus described my invention, what I claim, is—

1. In a device for gauging the hinge recesses of doors and door frames, a plurality of channel-shaped gauge members having

- medial openings affording play for a routing tool, plates arranged in pairs registering with the channels of and adjustably secured to each member adjacent the medial opening, certain of said plates extending beyond said members being overlapped and slotted for rendering the plates extensible, and means for clamping and preserving the alinement of the plates.
2. In a device for gauging the hinge recesses of doors and door frames, a plurality of normally open frames, slotted plates extending between and connecting the frames, the corresponding ends of said plates being adjustably secured to the frames adjacent said openings and being movable longitudinally, the extended portions of said plates being overlapped and being equipped with means for rendering the plates extensible for varying the spacing of said members, and means for clamping and preserving the alinement of the extended portions.
3. A device for gauging hinge recesses of doors and door frames, comprising a plurality of channel-shaped frames having central openings affording play for routing tools, flat plates having their corresponding ends slidably mounted in said channels, the opposite ends of the plates being overlapped beyond the frames, means passing through said overlapped portions for adjusting the frames longitudinally, and means passing through the frames and the corresponding ends of the plates for adjusting said ends relatively to the openings of the frames.
4. A device for gauging the hinge recesses of doors and door frames including a plurality of normally open sections, alining plates arranged in pairs for spacing and connecting the sections, certain of said plates extending beyond the facing ends of the sections and overlapping each other, the lapped portions of the plates being formed with registering slots, means passing through said slots for adjustably holding the plates together, and the unlapped ends of said plates being adjustably secured to the sections adjacent said openings for gauging the height of the recesses.
5. In a device for gauging hinge recesses of doors and door frames, a plurality of elongated channel-shaped frames having openings for the play of a routing tool, plates slidably longitudinally in the channels for gauging the height of the recesses, a number of said plates extending towards the adjacent frames and being overlapped and slotted longitudinally, means for clamping in the overlapped portions of the plates and for preserving the alinement of the plates, and means for adjustably securing the opposite ends of the plates in said channels.
6. A hinge recess gauge including a plu-
- rality of members having medial openings affording play for a routing tool, plates for connecting said members end to end, the corresponding ends of the plates being adjustably secured to said members and movable towards and from said openings, the opposite ends of the plates extending towards the adjacent members and being overlapped and equipped with means for rendering the plates extensible for varying the spacing of said members, and means for clamping the plates and for preserving the true alinement of the plates and said members.
7. In a device for gauging hinge recesses of doors and door frames, a plurality of normally open frames, alining plates for spacing the frames, said plates extending beyond the facing ends of the frames and overlapping each other, the lapped portions of the plates being formed with registering slots, means passing through said slots for adjustably holding the plates together, the unlapped ends of the plates being adjustably secured to the frames adjacent said openings for gauging the height of the recesses, means for gauging the breadth of the recesses, and means for gauging the adjusted extremities of the device.
8. In a device for gauging hinge recesses of doors and door frames, a plurality of elongated frames having openings for the play of a routing tool, plates for spacing the frames, the portions of said plates extending between the frames being overlapped and slotted longitudinally, bolts playing in said slots for clamping and maintaining the adjustment of the plates and frames, means for adjustably securing the unlapped ends of the plates to the frames, and graduated members adjustably mounted at the extremities of the device for spacing the uppermost recesses from the lintel of the door frame.
9. In a hinge recess gauge, a plurality of members having openings affording play for a routing tool, plates for connecting and spacing said members longitudinally, said plates being adjustable relatively to the members, said plates extending beyond the members, means for maintaining the adjustment of said members, short plates mounted at the extremities of the device cooperating with the longer plates for gauging the height of the recesses, and means for guarding the said extremities.
10. In a device for gauging the hinge recesses of doors and door frames, a plurality of frames arranged for the play of a routing tool, flat metal strips for connecting said frames substantially end to end, the portions of the strips extending beyond the adjacent frames being overlapped for rendering the device extensible longitudinally, the frames at the extremities of the device being equipped with end-gauging means adjust-

ably secured to the short plates, and means carried by each frame for gauging the breadth of the recesses.

11. In a device for gauging hinge recesses of doors and door frames, a plurality of normally open members, elongated slotted plates for gauging a number of recesses spacing said members, the corresponding ends of said plates being overlapped and adapted to be moved longitudinally for varying the spacing of the recesses, means for clamping the lapped portions of the plates, means for adjusting the opposite ends of the plates relatively to the openings in said members, and means for adjusting the extremities of the device for defining the space between the uppermost hinge recesses and the lintel of the door frame.

12. In a device for gauging hinge recesses of doors and door-frames, a plurality of frames adapted to guide a routing tool, flat plates of different lengths supporting the frames, the longer plates projecting beyond the facing ends of the frames and being overlapped for rendering the plates extensible for varying the spacing of the frames, means for varying the play of the routing tool for cutting recesses of different areas, and means carried by each frame for temporarily securing the device to the door and door frame.

13. A hinge recess gauge, comprising a plurality of normally open frames, one for

each recess, similar flat metal strips for connecting and spacing said frames, said strips being arranged in pairs, the facing ends of each pair being slidably secured to the corresponding frame adjacent the opening, the strips carried by the facing ends of the frames extending beyond the frames and being overlapped and said overlapped portions being formed with longitudinal slots for rendering the strips extensible, and means engaging the slots of said strips for clamping the strips.

14. A recess gauge for door hinges, comprising a plurality of normally open frames, one for each recess, similar flat metal strips for spacing the frames, said strips being arranged in pairs, and the facing ends of each pair being secured to the corresponding frame adjacent the opening, end-gauging members adjustably mounted at the extremities of the gauge, transversely movable gauging members mounted on the facing ends of each pair of strips, said members having points adapted to enter and to be adjusted to the height of molded recesses of metal door frames for facilitating gauging the corresponding recesses of a door to coincide with the molded recesses, and means for adjustably connecting the corresponding strips of the adjacent frames.

In testimony whereof I affix my signature.

RAY L. CARTER.
